UNITED STATES PATENT OFFICE.

EDWARD M. LAPPORTE, OF CHICAGO, ILLINOIS.

BLOOMERS.

Application filed February 11, 1925. Serial No. 3,347.

To all whom it may concern:

Be it known that I, EDWARD M. LAPPORTE, citizen of the United States, residing at Chicago, in the county of Cook and State of Illinois, have invented certain new and useful Improvements in Bloomers; and I do hereby declare the following to be a full, clear, and exact description of the invention, such as will enable others skilled in the art to which it appertains to make and use the same.

My invention relates to bloomers and in general aims to provide a simple construction and arrangement of the parts where by the finished garment will afford numerous highly desirable advantages. In some of its particular objects, my invention aims to provide bloomers in a construction enabling relatively few parts to provide the desired freedom of movement and fullness without pressing seams either in the crotch or in other portions of the garment where their presence might cause discomfort. It also aims to provide a rear opening and closing construction which will effectively afford a closed crotch either with or without the use of fastening means, such as a button. Furthermore, my invention provides a construction which will readily lend itself to the use of elastic bands both at the waist and at the lower ends of the leg portions, and one which can be constructed advantageously from only three main portions. Still further and also more detailed objects will appear from the following specification and from the accompanying drawings, in which

Fig. 1 is a somewhat flattened front view of the finished garment.

Fig. 2 is a similar rear view, with portions of the back member cut away.

Fig. 3 is a horizontal section taken through Fig. 2 along the line 3—3.

Fig. 4 is a vertical section taken along the line 4—4 of Fig. 1.

Fig. 5 is a perspective view showing the garment as it appears when in use.

Fig. 6 is a perspective view drawn on a larger scale than Fig. 5, with a portion of the flap turned back.

Fig. 7 is a view showing the shapes of desirable patterns for three main portions of the garment and also indicating which portions of the upper parts are adjoined.

In constructing a garment after the manner of the drawings, I employ three main

portions which may be cut from patterns shaped as shown in Fig. 6, although I do not wish to be limited to the particular cut of these patterns as there shown. The cloth portions cut according to these patterns include two leg members 1 and 2 which have oppositely directed upper lateral edges 3 and 4 adapted to be secured to each other along a vertical seam 5 extending downwardly at the front of the garment for some distance from the waistline. Each of these leg members also has adjacent to its lower end a pair of oppositely directed edge portions adapted to be secured to each other along a vertical seam 5 so as to constitute a tubular leg-inclosing portion which has its seam disposed along the inside of the leg. These adjoined lateral edge portions are the edges 6 and 7 in the part 1 and the edges 8 and 9 in the part 2. In practice, I desirably introduce elastics at the lower end of each of these leg portions and also along the waist or adjacent to the initial top of the parts 1 and 2, although I do not wish to be limited to the use of elastic means for securing any part of my present garment in position.

Interposed between the upper portions of the parts 1 and 2 at the rear of the garment is a back member 10 which has an upper edge portion 11 cooperating with the upper edge portions 12 and 13 of the parts 1 and 2 in affording the upper or waist end of the garment. This back member 10 widens downwardly and is permanently secured along one of its lateral edges to the adjacent lateral edge of the upper portion of one of the leg parts, but is secured to the other leg part only adjacent to the waist and along the inner side of the lower tubular portion of that leg part. Furthermore, the lateral edge of the upper leg part to which the back part is permanently secured is desirably recessed after the manner shown at the edge 14 of the part 1 and the lateral edge 15 of the back part as secured thereto is correspondingly convexed, all as shown in Fig. 7. The opposite lateral edge 16 of the back part may be substantially straight as shown in Fig. 7 and this edge overlaps the adjacent (or rearwardly lateral) edge of the leg part 2 to a considerable extent, thereby forming an effective closure for the garment when in use. This closure may be made all the more effective by

providing the back part and the overlapped leg portion with cooperating fastening means, such as the button 18 and the button-hole 19 shown respectively on these parts, 5 although the general construction and arrangement of my garment is such that the use of a button or other equivalent fastening means is not essential.

The lower end of the back part 11 10 is curved so as to afford a downwardly convexed bottom edge 20 in the cloth part as originally cut, but this bottom is re-curved on itself and turned upwardly at the front of the garment where it is secured to 15 lateral edge portions of parts 1 and 2 along the edges of opposed recesses 21 and 22. The back part 10 is cut of a considerably greater width than the spacing between the edges 14 and 17 when the garment is in use, 20 thereby producing a considerable fullness both at the rear of the garment and also in the lower recurved portion of this back part.

Furthermore, the leg part 2 which is overlapped in a largely unsecured manner 25 by the edge 16 of the back part desirably has adjacent to its lower leg edge 8 a sharply tapering projection 23 directed towards the companion leg part. This projection has its initially lower edge secured 30 to the upward extension of the seam adjoining the edge portions 8 and 9 of the part 2, or along the juncture of the adjacent end of the edge 20 with the upper part of the said edge 8. By providing this pointed extension, and securing it in the manner described, I secure an additional fullness at 35 the rear of the corresponding leg, thereby increasing the comfort of the garment and the readiness with which it may be manipulated. 40

Since the front seam extends only part way down from the waist to the normal bottom of the back member, and since the leg members are formed to afford an increasing 45 fullness as they extend upwardly, the seams of the garment will not be disposed where they would afford discomfort, and it will be noted that there are no seams in the crotch. Moreover, since the right-hand portion of the back part overlaps the part 2 to 50 a considerable extent, gapping is prevented

even if no button is provided for enhancing the closure effect.

However, while I have illustrated the garment as having its main parts constructed 55 from portions having certain highly desirable shapes and proportions, I do not wish to be limited to these, as many changes might obviously be made in the same. For example, the part of the garment which I 60 have termed the back part may be secured to the leg part 2 along its entire edge 16, so as to adapt these bloomers for gymnasium use, in which case my distinctive construction affords similar advantages of unusual 65 comfort. Furthermore, it will be obvious that garments can be constructed after the manner of my invention out of materials varying widely in cost and appearance.

I claim as my invention:—

70

1. A pair of bloomers composed of a pair of leg sections having connected front side edges, and having spaced rear side edges, a back section extending downwardly from the top edges of the leg sections and connected along one side edge to the rear side edge of one leg section, and having the central part of its other side edge free and connected at the top thereof to the other leg section, the lower part of the back section being 75 curved upwardly to form a crotch and being connected to the adjacent parts of the leg sections, the rear side edge of the said other leg section having an upwardly extending extension which is connected to the adjacent parts of the front, to provide fullness, the lower end of the free side edge of the back section being connected at the line of juncture between the rear side edge of the adjacent leg section and the adjacent part of 80 the back section.

2. A pair of bloomers in accordance with 85 claim 1 and wherein the lower end of the free side edge of the back section extends for a distance below the extension and 90 wherein the said free side of the back section overlaps the extension and its connection to conceal each of the latter.

Signed at Chicago, Illinois, February 7, 1925.

EDWARD M. LAPPORTE.
